UNITED STATES PATENT OFFICE.

JOHN FREDERICK BILLENSTEIN, OF CLEVELAND, OHIO.

STAIR-CARPET FASTENER.

1,126,361.

Specification of Letters Patent. Patented Jan. 26, 1915.

Application filed October 3, 1914. Serial No. 364,557.

To all whom it may concern:

Be it known that I, JOHN FREDERICK BILLENSTEIN, a citizen of the United States, residing at Cleveland, in the county of Cuyahoga and State of Ohio, have invented a certain new and useful Improvement in Stair-Carpet Fasteners, of which the following is a full, clear, and exact description.

The object of this invention is to provide cheap, effective, and easily applied means for securing stair carpet upon stairs.

The invention consists in the construction and combination of parts hereinafter described and pointed out definitely in the claims.

In the drawing Figure 1 is a side elevation of a stair fastening member adapted for use at the left edge of the carpet. Fig. 2 is a front elevation of the same. Fig. 3 is a front elevation of the lower ends of the two fastening devices and the stair rod which they hold when these things are in use, the lower stair tread, and the carpet thereon being shown in section. Fig. 4 is a sectional side elevation of one stair tread and one riser and part of another tread with the carpet secured thereto by means of this invention. Fig. 5 is a full sized sectional side elevation in the plane of line 5--5 on Fig. 3; and Fig. 6 is a perspective view showing the lower end of the left fastening device and the carpet and the adjacent stair tread and riser.

A complete fastening device for each step of the stairs includes a left handed gripper bar A, a right handed gripper bar A¹, and a rod B which extends from one gripper bar to the other over the carpet, and is held, adjacent to its ends, by both gripper bars. The two gripper bars A and A¹ are alike, except that they are right and left handed, as shown. That is, one is adapted for use alongside of the right edge of the carpet C, and the other is adapted for use alongside of the left edge of the carpet. Each of these gripper bars is a thin flat spring steel bar, having one or more upwardly extended prongs 10 at its upper end, and one or more downwardly extended prongs 12 at its lower end. In order that these bars may be adapted for use on stairs whose risers are of different heights, each bar is constructed with an extension member a at its upper end. This member has a longitudinal slot a', through which passes the clamping screw B which screws into the bar A. The opposed

and engaging surfaces of this bar and extension member are knurled or otherwise roughened.

The left hand vertical edge 8 of the left gripper bar, and the right hand edge 9 of the right gripper bar will, for convenience, be referred to as the outer edges thereof, and the other edges as the inner edges. The lower end of each of these bars is formed with a laterally outward projection 14 which extends beyond the outer vertical edge 8 or 9 of said bar. A slot 15 is formed in the bar adjacent to its lower end, and it extends from its inner edge outward, and preferably at a slight angle downward, into said lateral extension and to a point beyond or outside of the vertical outer edge of the bar. Adjacent to the outer part of the lateral extension 14, and integral therewith is a forwardly and upwardly bent U-shaped clamp 16. When these gripper bars are formed and tempered, they are given a permanent bend or set, as shown in Fig. 1; that is to say, between their ends, they are bent rearward. When these gripper bars are put to use, the lower prongs 12 are pressed down through the carpet into the stair tread T, on which it is laid, close to the edge of said carpet. Then the edge of the carpet is passed from behind the lower end of the gripper bar, through the slot 15 into a position in front of the gripper bar. When this has been done, the operator, taking hold of the upper end and the middle of the gripper bar, will bend the middle part of said bar forward so that the upper end may be passed beneath the overhanging portion of the tread T' immediately above that on which the carpet has been laid, as stated. The upper prongs 10 will then be allowed to penetrate this overhanging part of the tread T', especially when the middle part of the gripper bar is pushed backward between the upper and lower prongs, and it will so bend back until it engages the riser R intermediate of the two tread parts of the stairs which have been referred to. It is obvious that substantially all of both gripper bars which are above the slot 15, will be behind the carpet and thereby concealed from view.

The rod 17 is, as stated, not essential, but it is preferably used. When so used, it may be slipped downward into the embrace of the U-shaped hooks 16, or may be threaded endwise through them. In either event, it

will lie against the carpet along the line where said carpet bends upward from the horizontal to the vertical position, and will help to hold the carpet smooth and straight; 5 and likewise it conceals from view that part of the lower end of the gripper bars which are below slot 15, but outside of the carpet.

Having described my invention, I claim:

1. A stair carpet fastening device, comprising a thin, flat spring metal gripper bar having an upwardly projecting prong at its upper end, and a downwardly projecting prong at its lower end, and having, adjacent to said lower end, an 10 outward lateral extension, and there being a slot in said gripper bar adjacent to its lower end, which slot extends from the inner edge of said gripper bar outward into said lateral extension and beyond 15 the plane of the outer edge of the gripper bar.

2. A stair carpet fastening device, comprising a thin, flat spring metal gripper bar having an upwardly projecting prong at its 20 upper end and a downwardly projecting prong at its lower end and having adjacent to said lower end an outward lateral extension, and there being a slot in said gripper bar adjacent to its lower end, which slot extends 25 from the inner edge of said gripper bar outward into said lateral extension and beyond the plane of the outer edge of the gripper bar, and said gripper bar having a forwardly and upwardly bent U-shaped 30 clamping hook which is integrally connected with the lower edge of said outward lateral extension.

3. A stair carpet fastening device comprising a thin, flat spring metal gripper bar having a downwardly projecting prong at 40 its lower end and having an outward lateral extension adjacent to its lower end, and there being a slot which extends from the inner edge of said gripper bar outward into said lateral extension and beyond the plane 45 of the outer edge of the gripper bar, combined with an extension member adjustably connected with the upper end of said gripper bar, and having an upwardly projecting prong formed on its upper end. 50

4. In a stair fastening device, the combination of a right gripper bar, and a left gripper bar, each of which is made of thin flat spring steel, and has an upwardly extended prong at its upper end, and a downwardly extended prong at its lower end, and each of said bars having adjacent to its lower end an outward lateral extension, and there being in each bar, adjacent to its lower end, a slot which extends from the inner 60 edge of the bar outwardly into said lateral extension and beyond the plane of the outer edge of said bar, and each of said bars having also adjacent to its lower end and integral with the lateral extension thereof a forwardly and upwardly bent U-shaped hook, and a stair rod which extends between and goes through both hooks and is held thereby. 65

In testimony whereof, I hereunto affix my signature in the presence of two witnesses. 70

JOHN FREDERICK BILLENSTEIN.
